FUEL OIL HEATER

Nikolaus Engelmann, Philadelphia, Pa.

Application April 13, 1931. Serial No. 529,750

3 Claims. (Cl. 123—122)

This invention relates to fuel oil heaters for internal combustion engines.

It is among the objects of the invention; to provide a fuel oil heater of simplicity and economy of construction; to provide an attachment for standard internal combustion engines normally using gasoline for fuel whereby fuel oil may be used; to provide a fuel oil heater in which in effect fuel oil is distilled so that the 10 lighter portions thereof are used to form a combustible mixture in an internal combustion engine while the heavier portions are caused to settle and be divided out from the fuel; and many other objects and advantages as will be 15 come more apparent as the description proceeds.

In the accompanying drawing:

Fig. 1 represents a fragmentary side elevation of the fuel oil heater as it may be provided in the invention,

20 Fig. 2 represents a side elevation of the invention applied to an ordinary automobile internal combustion engine,

Fig. 3 represents a vertical section partially in full lines of the oil heating device which may 25 be used in the form disclosed or to form the basis for the helical coils shown in Figs. 1 and 2,

Fig. 4 represents a fragmentary end elevation partially in section of the termination of the oil heating element, and

30 Fig. 5 represents a fragmentary enlarged section of the upper end of the oil heating device.

Referring to Fig. 3, there is provided an outer tube 10 one end of which is closed as at 11, and the other end of which is closed by a header 12.

35 A smaller tube 13 passes through the header and is substantially concentrically disposed in tube 10 and terminates in an open mouth 14 beneath the closed end 11 and is preferably provided with a series of holes 15 in slightly spaced relation 40 from the open mouth 14. An inlet pipe 16 is connected with the header 12 at one end so as to communicate with the interior of the pipe 10 and extends to any suitable source of supply such as a pump, not shown, or such as the vacuum tank 17 disclosed in Fig. 2. A settling chamber or sediment trap or tank 18 connected by pipe 20 to the header 12 is so disposed as to receive and hold the heavier particles or components of the fuel oil entering through pipe 16.

45 Although the device shown in Fig. 3 may be used as shown and associated with any desired form of heater, it is preferable that the double tube comprising inner and outer tubes be twisted in the form of a helix, as shown in Figs. 1 50 and 2, to embrace a source of heat such as the

exhaust manifold 21 of an internal combustion engine. It will be observed that the upper end of the double tube extends vertically from the helical turns and that the closed end 11 of the tube 10 is disposed in such horizontal position relative to the vacuum tank 17 that the normal fuel level in such tank is slightly below the closed end 11 as well as below the open mouth 14 of the inner tube 13. Such level in the intake tank is, however, normally slightly above the row of 60 holes 15 in the tube 13. The inner tube 13 is extended beyond the header 12 toward the carburetor 22 of the internal combustion engine 23 disclosed in dotted lines in Fig. 2 and is operatively coupled with such carburetor 22. Preferably 65 an electrically energized heating unit 23 is provided close to the carburetor so as to suitably heat the oil contained in tube 13 in order to start the motor.

70 It will be observed that the arrangement is such, as shown in Fig. 2 for instance, that the settling chamber or tank 18 is at a low point relative to the heater and to the coils so that the heavier portions may flow by gravity into the settling chamber.

75 The arrangement of the entire device is preferably such that the fuel oil may flow by gravity from the vacuum tank 17 or be pushed by a pump, if such is used, through pipe 16 into large pipe 10 in which the level of fuel raises until it substantially attains the level in the vacuum tank 17. As this is above the level of the apertures 15 in tube 13 oil may flow through these relatively small holes to fill the inner tube 13. Thus the tubes 10 and 13 are both filled with fuel to a point 80 below the open mouth 14 of the inner tube 13, and, of course, below the level of the closed end 11 of the outer tube 10. The electrically heated device 23 may be energized in order to raise the temperature of the oil in pipe 13 to a point at 85 which it may form a combustible mixture with air in the carburetor 22. After the motor has been started the exhaust gases passing through exhaust pipe 21 will heat the oil contained in the outer tube 10, and, of course, will also, through conduction, heat the oil within the portion of tube 13 contained within tube 10. This heating of the oil 90 will result in the volatile portions working toward the upper end of the pipe 10 while the heavier or thicker portions, particularly in such forms of the device as shown in Figs. 1 and 3, will move toward the bottom of the device, to be eventually disposed and entrapped in the sediment trap 18. 95 For this purpose it is preferred that the turns of the helix and the disposition of the pipes gen-

100 105 110

erally be such as to permit gravitational flow of the heavier or less volatile particles toward the sediment tank 18. As the oil in both tubes is heated there is expansion which is permitted in the upper end of tube 10 during which the oil level may raise to a point above the open mouth 14 of tube 13 so that the thinner and more volatile oil flows directly into the tube 13 through such mouth 14, as well as through the apertures 15.

10 The advantages of the invention will be manifest as will the fact that many changes and modifications may be made in the invention without departing from the spirit and scope of the invention as set forth in the appended claims.

15 I claim:

1. In combination, an internal combustion engine having an exhaust conduit, a pipe heatably associated with said manifold, each end of said pipe being closed, a second pipe extending through one closed end and having an open end in slightly spaced relation from the other closed end of the first mentioned pipe, said inner and outer pipes including a vertical portion, means for introducing fuel into the first mentioned pipe to a level initially below the level of said second mentioned pipe and so arranged that as said fuel is heated in said first mentioned pipe the fuel may expand so as to flow through the open end of said second mentioned pipe, a carburetor for said internal combustion engine, and means effecting communication between said second pipe and said carburetor.

2. In combination, an internal combustion

3. In a fuel heater for internal combustion engines, an outer pipe having two headers, an inner pipe passing through a header and having an open mouth in slightly spaced relation to the other header, a fuel inlet conduit passing into said first mentioned outer pipe, said inner and outer pipes being coiled to contactingly embrace an exhaust conduit of an internal combustion engine, said inner and outer pipes terminating in a vertically upstanding portion above the coils, a sediment trap communicating with the outer pipe at a low point thereof, said inner pipe continued beyond the header to form a connection to a carburetor, and an auxiliary heating device operatively associated with said extension of the inner pipe.

NIKOLAUS ENGELMANN.
